CLAIM

The ornamental design for an adapter assembly, as shown and described.

DESCRIPTION

FIG. 1 is a front perspective view of an adapter assembly according to a first embodiment of our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top elevation view thereof; and,

FIG. 7 is a bottom elevation view thereof.

Broken lines are environmental only and form no part of the claimed design.

The portions shown in a pattern of stipple illustrate areas of contrasting appearance.

1 Claim, 4 Drawing Sheets
